BALLAST EMPLOYING PLURALITY OF
TEMPERATURE SENSITIVE FUSES
George L. Wolfert, Danville, Ill., assignor to General
Electric Company, a corporation of New York
Filed July 9, 1965, Ser. No. 470,853
9 Claims. (Cl. 317—40)

The invention relates to a ballast for fluorescent lamps, and particularly to an improved ballast that employs a plurality of temperature sensitive fuses.

A temperature sensitive fuse for a fluorescent lamp ballast is described and shown in a patent application entitled, Ballast Apparatus Utilizing Temperature Responsive Fuses, filed on Oct. 3, 1960, in the name of Walter C. Mansfield, Jr., Ser. No. 59,867 (now Patent No. 3,201,646). In that application, a single temperature sensitive fuse is shown connected in series with one of the input power leads to the lamp ballast. The fuse is internally positioned at a location in the ballast that is temperature critical or at a location in the ballast that indicates the condition of the ballast. When, for any reason, the temperature at this location exceeds a predetermined fuse response temperature, the fuse opens the input lead so as to remove power from the ballast. Normally, the fuse cannot be replaced because of its location. Thus, the opening of the input lead is permanent so that the ballast is permanently disabled. Normally, opening of the input lead by the fuse responding to an excessive temperature and permanent disability of the ballast are preferred to the ballast overheating and damaging the fluorescent lamp, the lamp fixture, and the surroundings. But opening of the input lead and permanent disability of the ballast because of a defect in the fuse are wasteful and frustrating.

Accordingly, an object of the invention is to provide a ballast employing a plurality of temperature sensitive fuses that protect the ballast from overheating.

Another object of the invention is to provide a ballast employing a plurality of parallel-connected, temperature sensitive fuses coupled in series with a preselected lead of the ballast to disable the ballast if it becomes overheated, and to maintain the ballast in operation as long as one of the parallel-connected fuses is operative.

Another object of the invention is to provide a ballast employing at least two temperature sensitive fuses that are connected in a parallel circuit, the parallel circuit being connected in series with one input power lead to the ballast so that if one fuse operates and opens because of a fault in the fuse, the ballast remains operative until the other fuse operates and opens.

Briefly, these and other objects are achieved in accordance with a preferred embodiment of the invention by two heat sensitive fuses connected in a parallel electrical circuit. The parallel circuit is preferably connected in series with one of the input power leads to the ballast. The fuses are preferably and respectively positioned on each side of the ballast primary winding inside the ballast case. If one fuse opens because of a fault in that one fuse, the other fuse permits the ballast to continue operating. However, if the ballast actually becomes overheated for any reason, both fuses will respond and open the input power lead. Thus, the desired overheating protection is provided, but the disability of the ballast because of a faulty fuse is practically eliminated and the reliability of the ballast is increased. In other embodiments of the invention, the parallel circuit may be connected in series with other ballast leads, or the fuses may be positioned at other locations.

The invention may be better understood from the following description given in connection with the accom-

2

panying drawings. The scope of the invention is given in the claims. In the drawings:

FIGURE 1 is a top plan view of a ballast employing two temperature sensitive fuses arranged and connected in accordance with the invention;

FIGURE 2 is a section view of the ballast and fuses in a longitudinal section taken along line 2—2 in FIGURE 1;

FIGURE 3 is a schematic diagram of the ballast and fuses shown in FIGURES 1 and 2;

FIGURE 4 is a longitudinal section view of one embodiment of a temperature sensitive fuse that may be used in accordance with the invention;

FIGURE 5 is a transverse section view of the fuse taken along line 5—5 in FIGURE 4; and

FIGURE 6 is a longitudinal section view of the temperature sensitive fuse shown in FIGURE 4 after the fuse has operated in response to overheating.

As shown in FIGURES 1 and 2, a ballast employing the two temperature sensitive fuses in accordance with the invention is contained in a suitable metallic case or housing 10. Such a ballast usually comprises a shell-type core 14 preferably made of a plurality of layers of magnetic laminations. The laminations are typically arranged to form an elongated core having an inner leg and two side legs. The various ballast windings, which may include a primary winding A, a secondary winding D, and heater windings G, H, and J, are wound about this inner leg. One or more capacitors 16, 17 may also be used to provide part of the ballasting action, to improve the ballast power factor, and to provide starting. These capacitors 16, 17 may be housed in a single can that may be insulated from the case 10. Two temperature sensitive fuses 18, 19 are provided, and are preferably positioned at symmetrical and corresponding locations (relative to the longitudinal axis of the ballast) on the side legs of the core 14 near the windings A, G, H, J as shown in FIGURES 1 and 2. Suitable connections are made between the ballast components to provide the electrical circuit shown schematically in FIGURE 3. After such a ballast is assembled, a suitable filler 12, such as an asphalt compound that is electrically insulating and heat conducting, is used to surround the ballast components. When the filler 12 hardens, the ballast components are firmly held in the case 10. A suitable metallic cover (not shown), may be placed on top of the case 10 to form a completed assembly.

In the schematic diagram of FIGURE 3, the various electrical elements have the same reference numerals as their corresponding components shown in FIGURES 1 and 2. The case 10 is indicated by the dashed lines 10 in FIGURE 3. The fuses 18, 19 are indicated by rectangles and are coupled in parallel. The primary winding A and the heater winding J are coupled in series. One end of these windings A, J is directly coupled to one side of an alternating current power source, and the other end of these windings A, J is coupled through the parallel-connected fuses 18, 19 to the other side of the power source. One end of the secondary winding D is coupled to one end of the primary winding A. The primary winding A and the secondary winding D are coupled in typical autotransformer relation as indicated by the conventional polarity dots adjacent one end of each of these windings A, D. In accordance with this dot convention, a given polarity of voltage at the dotted end of one winding causes the dotted end of the other winding to have the same given polarity of voltage. The other end of the secondary winding D is coupled through the power factor capacitor 16 to one side of a fluorescent lamp 2. The other side of the lamp 2 is coupled to one side of a fluorescent lamp 1. The other side of the lamp 1 is cou-

pled to the heater winding J. The heaters for the lamps 1 and 2 are heated by the heater windings G, H, J as shown. The starting capacitor 17 is coupled across lamp 2. A magnetic shunt may be provided between the primary winding A and the secondary winding D to provide improved ballast operation. When power is applied to the primary winding A, the voltage across the primary winding A and the voltage across the secondary winding D are added and applied across the lamp 1 through the starting capacitor 17. After lamp 1 fires, an increased voltage is applied across the lamp 2 so that the lamp 2 is also fired. When the lamp 2 fires, its low voltage drop essentially short circuits the starting capacitor 17 so that current serially flows through the lamps 1 and 2 and through the power factor and ballasting capacitor 16. As will be seen in FIGURE 3, the ballast receives power from the alternating current source as long as at least one of the fuses 18, 19 provides an electrical circuit.

Examples of temperature sensitive fuses that can be used for the fuses 18, 19 shown in FIGURES 1, 2, and 3 are described and shown in the patent of Water C. Mansfield, Jr., mentioned previously herein. Another example of such a fuse is shown in FIGURES 4 and 5. FIGURE 4 is a longitudinal section view of one fuse 18 of the two fuses 18, 19 connected in the ballast in accordance with the invention; and FIGURE 5 is a transverse section view of the fuse 18 taken along line 5-5 in FIGURE 4. As shown in FIGURE 4, the fuse 18 has two leads or wires 20, 21 which may be solid or stranded, and which are connected to other circuits or elements in accordance with the invention. The inner ends of the two wires 20, 21 are joined to a generally cylindrical link 25 which may comprise an alloy of bismuth and lead. This joining may be accomplished by welding or molding. After the inner ends of the wires 20, 21 are joined to the ends of the cylindrical alloy link 25, the assembly may be encased in a casting 26 which may comprise a wax compound preferably having a melting temperature slightly below the melting temperature of the alloy link 25. If desired, the wires 20, 21 with their alloy link 25 and wax casting 26 may be wound with a suitable insulating tape as shown in FIGURES 1 and 2 to provide protection and strength for the fuse 18 while the ballast is being assembled. After the ballast is connected and assembled with the fuses 18, 19 in the desired location, the filler 12 may be poured around the various parts and the fuses 18, 19 as well. The fuse 18 shown in FIGURES 4 and 5 is constructed of the alloy and wax compound mentioned, the wax casting 26 being cylindrically shaped and approximately 1.0 inch long and 0.3 inch in diameter. The fuse is wrapped with tape so that none of the wax casting 26 is visible. This tape protects the fuse during ballast assembly and helps prevent the fuse from prematurely opening when the filler is poured. The alloy link 25 is approximately 0.375 inch long and 0.078 inch in diameter. Thus, there is preferably a minimum thickness of the wax casting 26 around the alloy link 25 of at least 0.10 inch. This fuse 18 is designed to open at temperatures of 118 degrees to 125 degrees centigrade.

Properly constructed fuses will carry the rated electrical current until they are externally overheated to their designed opening temperature. At a temperature below the designed opening temperature of the fuse, the wax casting 26 melts to provide a molten volume around the alloy link 25. When the designed opening temperature is reached, and while the wax casting 26 is still molten, the alloy link 25 melts (and generally tends to collect at one wire) so as to break the electrical connection between the leads or wires 20, 21. FIGURE 6 shows the fuse 18 after it has been subjected to the designed opening temperature of the fuse 18. It will be seen that there is no electrical or ohmic connection between the wires 20, 21.

If, during or after manufacture of a ballast in accord-

ance with the invention, one of the fuses 18, 19 opens its electrical path for some reason, such as the filler 12 being too hot, there is still a good chance that the other of the fuses 18, 19 will not open its electrical path. Thus, 5 one of the fuses 18, 19 provides an electrical path for the ballast and permits the ballast to operate under normal conditions. However, after the remaining good fuse is subjected to the design temperature of the fuse, it will 10 open its associated electrical circuit and disable the ballast. But if both fuses 18, 19 are good, as is more likely 15 the case, then the ballast will not be disabled until each of the fuses 18, 19 opens its respective electrical circuit. The reliability (defined as the probability that a given device will not fail for some length of time) provided by two parallel-connected fuses may be seen from the following expression:

$$R_T = R_1 + R_2 - R_1 R_2$$

In this expression, R_T is the total reliability of the two parallel-connected fuses, and R_1 and R_2 are the respective reliabilities of each of the two fuses. If the reliability of each of the two fuses is 0.9, then the total reliability of the two parallel-connected fuses is $0.9 + 0.9 - 0.81$ or 0.99. Thus, reliability is increased in accordance with 25 the invention. In the case of the two fuses mentioned, the reliability is increased by 10%.

The use of two fuses which must be disabled by an overheated condition to disable the ballast provides an 30 improved ballast. Such fuses are desirable to electrically open and disable the ballast and thereby remove the cause of the overheated condition. This protects the fluorescent lamp fixture, the fluorescent lamp, and their surroundings. However, such fuses are subject to improper operation 35 even though the ambient temperature has not exceeded the predetermined magnitude for the fuse. Therefore, the invention provides two such fuses connected in parallel and preferably located in the vicinity of the primary and heater windings of the ballast. If one fuse opens for an 40 improper reason, the ballast can still function. However, the second fuse will open in response to an overheated condition and disable the ballast. While the invention has been discussed and explained in connection with only one embodiment, persons skilled in the art will appreciate that 45 modifications of the invention may be made. For example, heat sensitive fuses having various dimensions, compositions, materials, and operating characteristics (such as sensitivity to rate of temperature rise) may be used to fill a particular need. The parallel fuses may be connected in either input lead and may be applied to ballast circuits other than the specific circuit shown and discussed. 50 The parallel fuses may also be connected in parts of the ballast circuit other than the input leads. Also, more than two heat sensitive fuses connected in parallel may be provided. Thus, a second pair of parallel connected fuses may be connected in series with the same input lead or the other input lead and placed at desired locations which are likely to become hot. Also, the temperature sensitive fuses may be positioned at locations other than shown in 55 FIGURES 1 and 2. For example, one fuse could be positioned in the vicinity of the primary winding and the other fuse could be positioned in the vicinity of the secondary winding. In such a case, and also in the case of fuses 60 symmetrically positioned, different designed opening temperatures may be desirable for manufacturing or operating reasons. However, it is generally preferable that similar fuses be positioned in substantially the same corresponding and symmetrical transverse locations relative to the longitudinal axis of the ballast so that both fuses are 65 subjected to approximately the same temperature conditions in the ballast. Therefore, while the invention has been described with reference to a particular embodiment, it is to be understood that modifications may be made 70 without departing from the spirit of the invention or from 75 the scope of the claims.

What I claim as new and desire to secure by Letters Patent of the United States is:

1. In a fluorescent lamp ballast circuit having at least a primary winding and a secondary winding coupled to a magnetic core, said ballast being supplied with electrical power through input leads, the improvement comprising: a plurality of temperature sensitive fuses each having a structure that opens the electric circuit through said fuse in response to the ambient temperature of said fuse exceeding a predetermined magnitude; means connecting said fuses in parallel; means connecting said parallel connected fuses in series with one of said input leads; and means positioning said fuses in said ballast case.

2. The improvement of claim 1 wherein said fuses are positioned at spaced locations relative to each other.

3. The improvement of claim 1 wherein said ballast has a longitudinal axis and wherein said fuses are located substantially in a plane transverse to said longitudinal axis and are located at substantially corresponding and symmetrical points relative to said longitudinal axis.

4. In a fluorescent lamp ballast having an elongated shell-type core with an inner leg and two outer legs, having at least a primary winding and a secondary winding wound about said inner leg, and having a housing for said ballast, the improvement comprising: first and second substantially similar temperature sensitive fuses; means electrically connecting said fuses in a parallel circuit; means connecting said parallel circuit in series with said primary winding for connecting said primary winding to an external power source through said fuses; and means respectively positioning said fuses at corresponding locations adjacent said outer legs in the vicinity of said primary winding.

5. In a fluorescent lamp ballast having at least a primary winding and a secondary winding coupled to a magnetic core and housed in a case, said ballast being supplied with electrical power through input leads, the improvement comprising: a plurality of temperature sensitive fuses each having a structure that opens the electric

circuit through said fuse in response to the ambient temperature of said fuse exceeding a predetermined magnitude; means connecting said fuses in parallel; means connecting said parallel connected fuses in series with one of said input leads; and means positioning said fuses in said ballast case.

6. The improvement of claim 5 wherein said fuses are positioned at spaced locations in said ballast case.

7. The improvement of claim 5 wherein said ballast has a longitudinal axis and wherein said fuses are located substantially in a plane transverse to said longitudinal axis and are located at substantially corresponding and symmetrical points relative to said longitudinal axis.

8. In a fluorescent lamp ballast having an elongated shell-type core with an inner leg and two outer legs, having at least a primary winding and a secondary winding wound about said inner leg, and having a housing for said ballast, the improvement comprising: first and second temperature sensitive fuses; means electrically connecting said fuses in a parallel circuit; means connecting said parallel circuit in series with one of said windings for connecting said one winding to an electrical circuit through said fuses; and means respectively positioning said fuses at predetermined locations relative to said core.

9. The improvement of claim 8 wherein said fuses have different operating temperatures.
